Primary Examiner — Christian P. McLean*Assistant Examiner* — Kristopher Michael Blechschmidt(74) *Attorney, Agent, or Firm* — Barry Choobin; Patent 360(57) **CLAIM**

The ornamental design for a fishing rod, as shown and described.

DESCRIPTION

FIG. 1 is a perspective view of a fishing rod, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines depict portions of the fishing rod that form no part of the claimed design.

1 Claim, 5 Drawing Sheets(56)
